GAME DEVICE

Kenneth C. Shyvers, Chicago, Ill.

Application May 2, 1935, Serial No. 19,363

14 Claims. (Cl. 273—121)

This invention relates generally to a game apparatus, and more particularly to games of the type in which an object is caused to be projected onto a playing surface to actuate mechanism for the purpose of bringing about certain desired results.

An object of the invention is to provide in a game of the character described novel and improved mechanism requiring a high degree of skill in timing the travel of the object projected onto the playing surface so as to cause the same to reach a certain destination on said playing surface in a predetermined period of time in order to obtain the best possible results.

Another object of the invention is to provide in a game apparatus of the character described novel and improved mechanism requiring a high degree of skill to properly time the travel of the object projected onto the playing surface, so that the same will reach a predetermined point on said playing surface in a predetermined period of time, and means associated with said mechanism for visibly indicating upon the completion of the shot whether or not a winning shot has been made.

A further object of the invention is to provide in a game apparatus of the character described, a movable member and means for stopping the movement of said member by the projection of an object onto the playing surface, whereby the proper timing of the travel of the object projected onto the playing surface will bring about the stopping of said member at a pre-selected point.

A further object of the invention is to provide in a game apparatus of the character described, a movable member in full view of the player operating the device and novel and improved mechanism for stopping said member by the projection of an object onto the playing surface, said member being brought to a stop upon the projected object reaching a certain destination on said playing surface, whereby by proper timing the travel of the object projected will bring about a stopping of said member at a pre-selected point, and visible indicating means for indicating when a winning shot has been made and also the value assigned to said winning shot.

A still further object of the invention is to provide a game apparatus of the character described having coin controlled means associated therewith and time mechanism for limiting the time within which the device must be operated after the actuation of the coin operated mechanism.

A still further object of the invention is to provide in a game apparatus of the character described including a playing surface and means for projecting an object onto said playing surface, and means provided on said playing surface for actuation by said projected object to bring about certain desired results if the travel of the object is properly timed, and means for rendering the game apparatus inoperative should the player take too long a time before projecting the object onto the playing surface.

A still further object of the invention is to provide in a game apparatus of the character described coin controlled mechanism capable of operation with coins of different denominations, and means associated with said device for visibly indicating the denomination on denominations of coins used in the actuation of the coin controlled mechanism.

A still further object of the invention is to provide in a game apparatus of the character described a novel and improved anti-tilting or telltale device to inform the owner or lessee of the game apparatus when the player has attempted to operate the same fraudulently, said telltale device being so constructed that it will attract the attention of the owner or lessee of the device even though the latter be at a considerable distance from the same.

A still further object of the invention is to provide in a game apparatus of the character described having means for projecting or propelling an object onto the playing surface of novel and improved means for visibly indicating to the player the amount of pull exerted on the propeller or plunger prior to the release of the same for imparting momentum to the projected object.

A still further object of the invention is to provide in a game apparatus of the character described novel and improved means for returning the projected object from the playing surface to a position where it may again be actuated by the plunger for further operation of the device.

A still further object of the invention is to provide a game apparatus of the character described, which will be simple in construction, assembly and operation, which may be produced along lines convenient for low cost manufacture, and which will be highly efficient for carrying out the purposes for which it is designed.

With the foregoing and other objects in view which will appear as the description proceeds, the invention consists in certain novel features of construction, arrangement and combination of parts hereinafter fully described, illustrated in

5

50

55

the accompanying drawings, and particularly pointed out in the appended claims, it being understood that various changes in the form, proportion, size and minor details of the structure 5 may be made without departing from the spirit or sacrificing any of the advantages of the invention.

For the purpose of facilitating an understanding 10 of my invention, I have illustrated in the accompanying drawings, a preferred embodiment thereof, from an inspection of which when considered in connection with the following description, my invention, its mode of construction, assembly and operation, and many of its advantages should be readily understood and appreciated.

Referring to the drawings in which the same characters of reference are employed to indicate corresponding or similar parts throughout the 20 several figures of the drawings:

Figure 1 is a top plan view of a preferred form of a game apparatus embodying the present invention;

Fig. 2 is a longitudinal vertical sectional view 25 of the same taken substantially on line 2—2 of Fig. 1;

Fig. 3 is a plan view of the underside of the playing board showing the arrangement of the mechanism mounted thereon;

Fig. 4 is a plan view of the mechanism arranged within the casing with the playing board removed;

Fig. 5 is a transverse sectional view taken substantially on line 5—5 of Fig. 4;

Fig. 6 is a view taken substantially on line 6—6 of Fig. 2;

Fig. 7 is a fragmentary sectional view showing the electrical connection between the playing board and its associated casing;

Fig. 8 is a transverse sectional view through the anti-tilting mechanism taken substantially on line 8—8 of Fig. 4;

Fig. 9 is a transverse sectional view through the time switch mechanism taken substantially on line 9—9 of Fig. 4;

Fig. 10 is a bottom plan view of the propeller mechanism with the improved indicating means associated therewith;

Fig. 11 is a fragmentary sectional view taken substantially on line 11—11 of Fig. 1; and

Fig. 12 is a diagrammatic view of the apparatus showing the wiring diagram therefor.

Stated generally, the invention comprises the provision of a playing board arranged in a suitable casing, the upper side of the board having a track provided thereon over which is adapted to travel a projected object, said track having a means provided thereon for actuation by a projected object to bring about the stopping of a rotatable member associated with a dial having numerical designations provided thereon. By properly timing the travel of the projected object, said rotatable member may be stopped at a pre-selected point on the dial, whereby the 65 player will obtain as his score one of the higher numerical designations. The upper surface of the board is also provided with visible indicating means for indicating the value of the score upon the completion of the shot in the event that a winning shot has been made by the player.

The device has also associated with it a time switch and coin controlled mechanism for actuating said time switch, whereby upon the insertion of a coin the rotatable member will begin 75 to rotate, said rotation continuing for a prede-

termined period of time depending upon the setting of the time switch. It will be necessary for the player to make his shot during that pre-determined period of time, that is, before the time switch has returned to its original position when it will be impossible to make the shot without the insertion of a new coin.

The device has also associated with it a plurality of coin chutes whereby one or more coins of different denominations may be employed 10 with the device for placing the same in operative position. There is also provided visible indicating means for informing the owner or lessee of the device at a glance the particular denomination or denominations of coins used by the 15 player in the operation of the device.

There is also provided automatic means for returning the coin chute or chutes to operative position immediately upon the completion of the shot in the event that the same is not a 20 winning shot. However, should there be a winning shot made by the player, there will be automatic means brought into operation for holding the coin slides in their inwardly projected position until the time switch has again 25 returned to its original position when the coin slides will be automatically returned to operative position.

Referring to the drawings in more detail, the reference character 10 designates generally a 30 playing board, the upper side of which provides a playing surface onto which may be projected an object such as a metal ball, marble, or the like, designated by the reference character 11. In the embodiment illustrated, the playing board 35 is mounted in a cabinet, designated by the reference character 12, said board being disposed at an inclination to the horizontal, the direction of tilt being upwards from the end at which the player stands.

The board 10 has provided on the upper surface thereof adjacent the lower end a suitable dial 13 upon which are provided numerical designations 14, said dial being substantially the same in construction as the well known clock dial. Co-operating with said dial is the pointer or hand 15 which is connected to a shaft 16 so as to rotate therewith, said shaft being mounted in a suitable bearing 17 provided therefor in the board 10 and having its lower end secured to a suitable 45 disk 18, the latter being in frictional engagement with the friction wheel 19 carried by a shaft 20.

The shaft 20 is journaled in a bracket 21 rigidly secured to a motor and has a worm wheel 22 fixedly secured thereon which is arranged for 55 constant meshing with a worm 23 carried by the motor drive shaft 24 of the motor 25. The motor 25 is secured to the underside of the board 10 by means of a U-shaped band 26, the free ends of which are secured to the underside of the 60 board by means of the screws 27 or in some other suitable and well known manner. The motor is electrically driven and when a circuit is closed to the same, the drive shaft thereof will impart rotary movement to the pointer or hand 15, the 65 same being arranged to travel in a clockwise direction over the dial 13.

Disposed directly below the dial 13 and fixedly secured within the board 10 are a plurality of circumferentially arranged spaced electrical contacts, generally designated by the reference character 28, said contacts, in the embodiment illustrated, being in the form of metal studs extending through insulated bushings 29 mounted in the board 10 and each of said studs having an 75

electrical conducting wire 30 connected thereto, the number of said fixed contacts 28 corresponding to the number of numerical designations appearing on the dial 13.

5 Mounted on the shaft 16 for rotation therewith in a plane directly above the upper surface of the playing board 10 and below the dial 13 is an arm 31 of conducting material, said arm being secured to the shaft intermediate its ends 10 and having at one end thereof a flexible wiper arm 32 secured thereto, said wiper arm 32 being arranged so as to pass over the contacts 28 as the arm 31 rotates with the shaft 16 to successively engage each of said contacts. In order to properly balance the arm 31, there is provided a flexible arm 32' connected to the arm 31, said arm 32' having the free end thereof engage the upper surface of the board 10 to ride along the same, but is of such a size and is arranged so as not 15 to contact or pass over any of the fixed contacts 28 (see Fig. 6). The shaft 16 to which the arm 31 is connected has associated with it a wiper arm which is connected by an electrical conduit 34 with one end of an electric current supply line 20 35 leading from the batteries B.

Arranged on the board adjacent the upper end thereof are a plurality of circumferentially arranged spaced light bulb sockets, each generally designated by the reference character 36, the 30 number of said sockets corresponding to the number of fixed contacts 28, and each of said sockets being connected by the electric conduit 30 leading from a fixed contact 28 disposed in the same corresponding position around the circumference 35 of the circle within which the contacts are arranged with that of the light socket to which it is connected. The other terminals for each of said light sockets is connected to an annular ring member of conducting material, generally designated by the reference character 37, which ring member may be secured to the underside of the game board by means of suitable screws 38 or in some other suitable and well known manner.

The light sockets 36 are provided with light 45 bulbs 41, which light bulbs will, of course, become illuminated upon the closing of the circuit to the particular socket within which the light bulb is disposed.

Provided on said game board adjacent each 50 socket is a numerical designation 42, which designation will designate the value or score that the player is entitled to when the apparatus is actuated so as to bring about a closing of the circuit to the particular light bulb arranged opposite 55 the designation 42. It will thus be noted that each of the fixed contacts 28 is arranged in a circuit with a corresponding light bulb, and when such circuit is closed, the light bulb will be illuminated to visibly indicate the value or score 60 that the player is entitled to by bringing about, through the operation of the device in the manner to be presently more fully described, the closing of the circuit to the particular light bulb illuminated.

65 The upper surface of the playing board is provided adjacent the right hand side thereof with a ramp 43 over which may be projected the ball 11 onto a section of track 44, the lower portion of which is in communication with the ramp 43 adjacent the lower end thereof. The ball is caused to travel up and around the ramp and onto the section of track 44 by means of the force imparted to it by the plunger 45.

Arranged intermediate the ends of the portion 70 75 of track 44 is an opening 46 within which the ball

is adapted to be received, and when said ball is deposited within said opening it will not be permitted to drop through the same, but will be held therein by means of a member 47 which is disposed directly below said opening and which is secured to a transversely arranged shaft 49, the ends of which are mounted in suitable brackets 50 secured to the underside of the playing board, as shown more clearly in Fig. 3 of the drawings.

The member 47 may be adjusted on the shaft 10 49 by means of the screw 51 which secures the member 47 to the shaft 49. Rigidly secured to the shaft 49 intermediate the ends thereof are three depending members 48, which members are arranged in a position so as to be actuated by 15 the coin slides associated with the coin operated mechanism, to be presently described, for imparting rotary movement to the shaft 49 to cause the arm 47 connected thereto to strike the ball 11 so as to force the same out of the opening 46 and 20 down the track onto the lower portion of the ramp 43 in position for actuation by the plunger 45. A suitable stud or screw 51' is provided on the underside of the playing board for limiting the movement of the shaft 49 in a clockwise direction, as viewed in Fig. 2 of the drawings.

The coin controlled mechanism for my improved game apparatus is of the usual and well known construction, and in the embodiment illustrated, there are provided a plurality of coin 30 chutes whereby the device may be operated with a single coin or with a plurality of coins of varying denominations. Thus, as shown in Figs. 1 and 4, secured to the front wall of the casing or cabinet 12 are the coin chutes 52, 53 and 54, which 35 chutes are provided with the coin slides 55, 56 and 57, respectively, which slides are provided with coin apertures to receive a coin of proper denomination for the actuation of the same. Thus the coin chute 52 is provided with a coin aperture of 40 a size to receive a nickel, the coin aperture in the chute 53 is of a size to receive a penny, whereas the coin aperture in the chute 54 is of a size to receive a dime. The slides 55, 56 and 57 are of such a size in length as to engage the depending 45 arms 48 carried on the shaft 49 when said slides are pushed inwardly after the insertion of the coin so as to actuate said shaft 49 to move the arm 47 connected therewith in a counter clockwise direction for ejecting the ball 11 from the 50 opening 46 to move said ball to a position adjacent the front end of the plunger 45, as shown in dotted lines in Fig. 1 of the drawings.

Each of the coin slides 55, 56 and 57 is provided with a projection 58, which projection is arranged 55 at such a point on its respective coin slide as to bring about a closing of a circuit to a light bulb located at the head of the casing 12, there being one such light bulb associated with each of said chutes, said light bulbs being designated by the 60 reference characters 59, 60 and 61. Thus, when the coin chute 52 is operated, the slide 55 thereof will close the switch 62-63 thereby completing a circuit to the light bulb 59, and when the coin chute 53 is operated, the slide 56 thereof will 65 close the switch 64-65 to close a circuit to the light bulb 60, and when the coin chute 54 is operated, the slide 57 thereof will close the switch 66-67 to close a circuit to the light bulb 61.

The illumination of said bulbs will inform the 70 owner or lessee of the game apparatus which of the coin chutes had been operated in placing the game in operative position, the circuits to said bulbs remaining closed until the slides have been returned to their normal original position in a 75

manner to be presently more fully described, at which time the switches controlling the circuits to said light bulbs will be opened. It will also be noted that should only one or two of such chutes be operated, the light bulbs associated with said particular chutes will be the ones that will be illuminated, the other remaining in the "off" position, so that the operator of the game may be able to tell at a glance from a distance the value 10 or score that the player is entitled to should a winning shot be made.

The entire mechanism is under the control of a suitable time switch, generally designated by the reference character 68, which time switch is 15 arranged in position to be actuated by the operation of either one or all of the coin chutes. Thus, in the embodiment illustrated, there is shown a bell crank, designated by the reference character 69, which is mounted in the bracket 70 provided therefor, said brackets being secured to the floor of the casing 12. Each of the coin slides is provided with a portion 90, shown in Fig. 2, which is adapted to engage the bell crank to rotate the same when the coin slide is moved inwardly.

25 The bell crank 69 is provided with a depending arm adjacent one end thereof designated by the reference character 71, said arm being arranged for engaging an arm 72 provided on the time switch 68 to move the said arm 72 in a clockwise direction, the latter being pivoted to a disk 73 by means of a stud 74. The upstanding pin 75 is provided on the disk 73 for limiting the movement of the arm 72 in one direction, said arm 72 being normally held against said upstanding pin 75 by 30 a spring 76, the free ends of which are secured to studs 77 and 78, the former one of said studs being provided on the disk 73 and the other of said studs being provided on the arm 72.

Thus when the depending arm 71 of the bell 40 crank 69 engages the arm 72 upon the actuation of either one or all of the coin slides, the arm 72 will be effective for rotating the disk in a clockwise direction. A spring 79 having one end secured to the depending arm 71 and the other end 45 to an arm 80 pivotally mounted in a bracket 81 secured to the front wall of the casing 12 will be effective for returning the bell crank 69 to its original position, the arm 72 permitting the arm 71 to ride past the same on its return movement. A stud 82 secured to the floor of the casing 12 is 50 provided for limiting the return movement of the bell crank 69.

The periphery of the disk 73 is adapted to be 55 in constant engagement with a stud 83 provided on an arm 84 pivotally secured intermediate its ends on a pivot 85 to a plate member 86 of the time switch 68 and a coil spring 87 normally urging said stud 83 into engagement with the periphery of the disk 73. The disk 73 is provided 60 with a notch 88 formed on its periphery arranged for receiving the stud 83, as shown in Fig. 12 of the drawings. The arm 84 is also provided with a depending stud 89 in contacting engagement with the movable contacts 91 and 92 which are 65 adapted to co-operate with fixed contacts 93 and 94, respectively, for completing a circuit to the mechanism through the batteries.

The time switch, which is generally designated 70 by the reference character 68, includes a pair of spaced plate members 87 and 95 rigidly secured to each other by means of the spacing studs 96, said plate members carrying a clock mechanism of usual construction, including a shaft 97 to which the disk 73 is rigidly secured for rotation therewith. The shaft is mounted in suitable

bearings provided therefor in the plate members 87 and 95 and has secured thereto, as shown at 98, one end of a main spring 99, the other end of which is secured to a depending projection 100 pressed out of the plate member 87, whereby the 5 actuation of the disk 73 by the bell crank 69 will tend to wind up the main spring 99, which spring will then return the disk 73 to its original position by the clock mechanism.

The disposition of the stud 83 within the notch 10 88 of the disk 73 will bring about a stopping of the rotation of the disk 73, and when in that position it will be noted that the movable contacts 91 and 92 will be forced out of engagement with their respective fixed contacts 93 and 94, 15 thereby holding said switches in an open position, as shown in Fig. 12. However, when the time switch 68 is actuated by the actuation of either one or all of the coin slides, the stud 83 on the arm 84 will be cammed out of the notch 88, thus 20 swinging the arm 84 in a counter-clockwise direction, thereby permitting the movable contacts 91 and 92 to engage the fixed contacts 93 and 94 for completing the circuit through the batteries B.

These contacts will remain closed until the 25 main spring 99 has returned the disk 73 to the position where the stud 83 will again be snapped into the notch 88, in which position the engagement between the contacts 91 and 93 and 92 and 94 will be broken. It will be noted that the time 30 switch 68 may be set or adjusted to vary the length of time that it will require to return the same after it has been actuated by the coin slides to its original contact breaking position. It is during the time that the contacts are closed that 35 the player must make his shot in order to be entitled to a score should a winning shot be made. In practice, it has been found that a period of time ranging from one minute to a minute and a half is sufficient time for the player to make a 40 shot and to permit the owner or lessee of the device to note the result thereof and to credit the player with the proper score should a winning shot be made.

Thus, with the completion of the circuit to the 45 batteries by the actuation of the coin chutes in the manner just described, the device is placed in operative position for the playing of the game by the player. It will be noted that upon the insertion of a coin or coins in the coin apertures of the 50 respective chutes and the pushing in of the coin slides, the said slides will strike the arms 48 carried by the shaft 49 to swing the latter in a position to cause the arm 47 to eject the ball 11 from the opening 46 to force the latter to roll into position against the free end of the plunger 45 in which position the said ball will be ready for actuation by the player.

The removal of the ball from its opening will permit an arm 101 carrying a contact 102 to be 60 moved in a counter clockwise direction by the spring 103 to engage a fixed contact 104 for closing a circuit to the motor 25 (see Fig. 12). The closing of this circuit will start the rotation of the shaft 16 and the arms 31 and pointer 15 65 connected with said shaft. The player now has either a minute or a minute and a half within which time to project the ball by the operation of the plunger 45 onto the track 44 for depositing the same within the opening 46. The object will 70 be to so control the speed of the ball so that the same will be received within the opening 46 at the instant when the hand 15 is disposed over one of the higher numerical designations on the dial 13, for the instant that the ball drops into 75

the opening it will actuate the arm 101 to break the contact 102—104, thereby instantaneously stopping the rotation of the motor which will bring about a stopping of the hand or pointer

5 15.

As already explained, it is only when the hand 15 is stopped, so that it is disposed above one of the numerical designations provided on the dial, that a circuit will be closed to the light bulbs 41 for only at that time will the wiper arm 32 carried by the arm 31 be in engagement with one of the fixed contacts 28 for completing a circuit to one of the light bulbs 41. Thus, should a shot be made by the player and the ball deposited in the opening 46 at the instant when the arm 32 is not in contacting engagement with one of the fixed contacts 28, the circuit to the motor will be broken by the swinging of the arm 101, due to the weight of the ball, in a clockwise direction about its pivot 105.

The arm 101 has associated with it an arm 106 which carries a contact 107, said contact being connected by a wire 108 to one end of a battery C. The other end of said battery is connected to a fixed contact 109 secured to the underside of the playing board 10, said contact being arranged for engagement by a movable contact 110 carried by the shaft 49, the contact 110 being connected by a wire 111 to one end of a solenoid 112, the other end of the solenoid being connected by a wire 113 to a contact 114.

The arm 106 also carries a contact 115 adapted for engagement with a contact 116 carried by a flexible arm 117 secured to the underside of the playing board, said arm being connected by a wire 118 to the annular conducting ring 37. The arm 106 is constructed of flexible conducting material and is arranged so as to form an armature for a solenoid 119, said solenoid being arranged in a circuit in series with the light bulbs 41, so that the same would be energized to contact the arm 106 should a circuit be closed to any one of said light bulbs 41.

One end of said solenoid is connected by a wire 120 to the conducting arm 106, and the other end is connected by a wire 121 to a line leading to the contact 94. The arrangement of the arm 106 is such that should a shot be made which is a winning shot a circuit will be closed to one of the light bulbs 41, the solenoid 119 will be energized and will hold the arm 106 in position to prevent the closing of the circuit 107—114, thereby preventing the energizing of the solenoid 112 for a purpose to be presently more fully described.

Each of the coin slides 55, 56 and 57 is provided on its side edge with notches 122 in which is adapted to be received one end of a pivoted latch arm 123, said arms being pivotally secured intermediate their ends by means of the pivots 124 and are normally held in a substantially horizontal position, as viewed in Fig. 12, by means of the springs 125 connected to said arms, one on each side of said pivot. Thus, when a coin slide is actuated and the same pushed forward, the arms 123 will first be moved in a counter-clockwise direction until the right hand edge of the arm 123 is received within the notch 122 or the position shown in Fig. 4, in which position the slides will be held by reason of the stop 126 carried by a core 127 mounted within the solenoid 112, said stops 126 preventing rotation of the pivoted members 123 in a clockwise direction.

Suitable springs 128 are provided for normally urging said coin slides outwardly, said springs

having one of their ends secured to the coin slide and the other end secured to a fixed stud provided on the front wall of the casing 12. The weight of the core 127 will normally hold the same in the position shown in Fig. 4. However, when the solenoid 112 is energized it will suck the core 127 upwardly, thereby permitting the springs 128 to withdraw the coin slides to place the same in position for further operation by the insertion of a coin in the coin apertures thereof.

The device has also associated with it a novel and improved tell-tale mechanism, whereby the operator of the game apparatus may be informed when the player has attempted to operate the same fraudulently by tilting the same from its normally proper operating position. This new mechanism comprises a cup shaped member 129 secured in a bracket 130 fastened to the front wall of the casing 12, said member 129 being provided with a depending portion 131 within which is provided a recess 132, said recess receiving for sliding movement therein a plunger 133 having a stem 134 secured thereto and extending through an opening provided therefor in the portion 131.

The plunger 133 is provided on its upper face with an annular ball seat 135 which has a slight concavity on its upper and ball supporting surface to support the ball 136. A coil spring 137 is disposed within the recess 132 and is arranged to normally urge the plunger 133, as viewed in Fig. 8. The stem 134 has associated with it adjacent its lower end a spring contact 138 which is disposed directly opposite a fixed contact 139.

Leading from the fixed contact 139 is a wire 140 to a light bulb 141 to which is connected a return wire 142 leading to the contact switch 92—94. The contact 138 is connected by a wire 143 to a line leading to the contact switch 91—93. The weight of the ball 136 is sufficient to normally hold the contacts 138 and 139 out of engagement with each other, thereby holding the circuit to the light bulb 141 open.

However, should the device be tilted or otherwise tampered with so as to dislodge the ball 136 from its seat 135, the spring 137 will urge the plunger 133 upwardly thereby bringing the contacts 138 and 139 into engagement with each other closing the circuit to the light bulb for illuminating the same. This circuit, of course, will be closed only when the switches 91—93 and 92—94 are closed, so that when the device has been actuated by the coin mechanism and the machine placed in position for the player to make his shot, and the player should tamper with the device while making his shot, the ball 136 will be immediately dislodged and the tell-tale light 141 illuminated. This will immediately show to the operator of the game apparatus that the device had been tampered with and that the player is, of course, entitled to no score. The advantage of a tell-tale device of this character is that the same may be observed by the operator of the game apparatus from some distance from the device without necessitating his walking over to the same to determine whether or not the tell-tale ball has been dislodged from its normal position as is necessary with tell-tale devices employed heretofore.

In order to replace the tell-tale ball in its operative position upon the coin chute or chutes being again operated, I have provided on the lower end of the stem 134 an annular disk 144 secured thereto by means of the nuts 145. Bear-

65

75

ing on said disk 144 is a bell crank arm 146 pivotally mounted in the bracket 81 connected to the front wall of the casing 12, said arm 146 being rigidly secured to the arm 80 to which the 5 spring 79 of the bell crank 69 is secured. Thus when the coin slide is pushed forwardly, the portion 90 thereof will engage the bell crank 69 to rotate the same, thereby exerting a pull on the spring 79, which pull will be transmitted through the arm 80 to the arm 146 for exerting a downward pull on the stem 134 to bring the plunger 133 with its ball supporting surface 135 flush with the bottom wall 147 of the cup shaped member 129, said bottom wall having a slight flair 15 so as to permit the ball 136 to roll onto its seat 135 and to be raised to the position shown in Fig. 8 when the bell crank 69 returns to its normal position. With the ball resting on the plunger 133, the contacts 138 and 139 will be 20 kept out of engagement with each other until the device is again tilted or otherwise manipulated to force the ball 136 to gravitate off its ball seat into the casing 129.

As already stated, an important feature of 25 the present game resides in the provision of mechanism whereby in order to obtain a high score the player must exercise a high degree of skill so as to properly time the travel of the ball from the propeller to the opening 46. In 30 order to facilitate this timing and to enable the player to gauge the amount of force imparted to the ball by the plunger, I have provided an improved indicating means whereby the amount of pull exerted on the plunger before the same 35 is released for striking the ball to project the same onto the track may be visibly indicated to the player.

In the embodiment illustrated (Fig. 1) there is 40 shown a dial 148 upon which appear suitable numerical indications 149, said dial having a hand 150 co-operating therewith for indicating to the player the amount of pull he has exerted on the plunger 45. The plunger 45 has associated with it a handle 151 by means of which it may be pulled back prior to its release against the ball for giving to the latter the desired momentum.

As shown more particularly in Fig. 10, the plunger 45 is surrounded by a coil spring 142, which spring has one end bearing against a collar 153 fixed to the plunger 45, so as to ride therewith. The collar 153 is provided with an upstanding pin 154 which is adapted to ride in the slot 155 provided therefor in the plate member 156 against the underside of which the plunger 55 and its mechanism is disposed.

Pivotedly secured to the underside of the disk 156 is a fork member 157 by means of a stud 158, said stud being arranged for rotation with the fork member 157 and extends through the disk 156 and has secured to the upper end thereof, as shown at 60 159, the pointer or hand 150, whereby the rotation of the fork member will impart similar rotation to the hand or pointer 150.

The fork member 157 is mounted between the 65 under surface of the disk 156, and the collar 153 with the stud 154 projecting up from said collar being received between the bifurcations of said member 157 with the result that a pull exerted on the handle 151 will impart a rotary movement to the member 157 and also to the indicator or pointer 150, and the angle of rotation of said member 150 will depend upon the amount or distance 70 that the plunger 45 has been pulled out. By 75 reason of this mechanism, a player will be able

to govern the amount of pull that he is exerting on the plunger before releasing the same and to thereby enable him to more successfully impart the desired momentum to the ball.

The operation of my improved game will be as follows: Upon approaching the device the player will find the mechanism in the position shown in Fig. 12, that is, with the ball 11 disposed in the opening 46 and the contact switches 91-93 and 92-94 open. The player will now insert a coin in 10 either one or all of the coin chutes 52, 53 and 54 and will push the same inwardly. The actuation of these coin slides will bring about simultaneously the rotation of the time switch to close the contact switches 91-93 and 92-94 and the 15 closing of the contact switches 62-63, 65-66 and 66-67 for illuminating the light bulbs at the head of the casing 59, 60, and 61, respectively, to indicate to the operator of the game that all of the coin chutes had been actuated.

The pushing forward of the coin slides will also 20 actuate the shaft 49 to cause the arm 47 associated therewith to eject a ball from the opening, the latter being received at the bottom of the ball ramp in position to be acted upon by the 25 plunger. The rotation of the shaft 49 will also bring about a closing of the contacts 109-110.

The removal of the ball from the opening 46 will immediately close the contact switch 102-104, thereby starting the rotation of the motor and 30 with it the pointer or hand 15. It will also be noted at this time that the contact 107-114 will be broken and the coin slides will be held in the position shown in Fig. 4 with the latch members 123 preventing the return of said coin slides by 35 reason of the stops 126 of the core 127 being arranged directly in the rear of said latch members 123.

With the hand 15 rotating, the player will now 40 attempt to shoot the ball up the ball ramp 43 onto 46 the track 44 to deposit the same within the opening 46 at the time when the hand 15 is disposed over one of the higher numerical designations on the dial 13. By reason of the dial 148 and hand 150, the player may determine just how much 45 pull he is exerting on the plunger in pulling the same out prior to releasing it against the ball for striking the same. It will also be noted that the player now has either a minute or a minute and a half depending upon the time that the time 50 switch is set for within which to complete his shot before the switches 91-93 and 92-94 are automatically broken by the return of the time switch 68 to its original position.

Assuming now that the player has made a shot 55 and the ball 11 is deposited in the opening 46 at the instant that the hand 15 is disposed over the designation "12" on the dial 13. With the hand 15 in this position it will be noted that the contact arm 32 will be in engagement with the 60 fixed contact 28 which is disposed directly below the numerical designation "12", thereby completing a circuit to the light bulb opposite the designation "10" at the upper portion of the board illuminating this bulb and indicating to 65 the player and operator that the player has made a winning shot which entitles him to a score of ten points.

The completion of the circuit to the light bulb 41 will simultaneously energize the solenoid 119 to 70 attract the armature arm 106 thereto thereby maintaining the contact switch 107-114 open and preventing the energizing of the solenoid 112 thereby maintaining not only the light bulb 41 in circuit, but also the light bulb 59, 60 and 61 and the 75

coin chutes in their pushed forward position. This position will be maintained until the time switch 68 has returned to its original position, thereby breaking the engagement between the contacts 91-93 and 92-94, the result of which will be to disenergize the solenoid 119 permitting the armature 106 to return to the position where there will be an engagement between the contacts 107 and 114, which engagement will bring about a closing of the circuit to the solenoid 112 causing the latter to pull up the core 127, thereby removing the stops 126 from engagement with the latch members 123 to permit the springs 128 to return the coin slides to their position.

15 It will be noted at this time that the contact 116 is mounted on a flexible member 117, which member will have sufficient resiliency to permit the closing of either switch 107-114 or a movement of the armature arm 106 when attracted by the solenoid 119 without breaking engagement between the contacts 115 and 116. Thus when the ball is projected onto the playing surface and the member brought to a stop with the arm 32 out of engagement with one of the contacts 28, there will be 20 no current flowing through the switch 115-116 as no circuit will be closed to the ring 37. In that case, the dropping of the ball into the opening will immediately force the arm 106 in a clockwise direction to bring the contacts 107-114 into engagement with each other to immediately close the circuit to the solenoid 112 for energizing the same and for pulling in the core 146 to permit the immediate return by the springs 128 of the coin slides. The return of these coin slides will immediately break the circuit to the light bulbs 59, 60 and 61. The game will again be in position to be operated when the time switch 68 has returned to its original position.

40 If after the insertion of a coin in the operation of the coin slide the player has tilted or otherwise tampered with the device, the tell-tale ball 136 will be dislodged from its support with the result that the plunger 133 will be forced upwardly closing the circuit to the tell-tale bulb 141. This will 45 immediately notify the operator that the device has been tampered with and that the player is not entitled to any score.

From the above it will be apparent that I have provided a novel and improved game which is 50 capable of operation with one or more coins of different denominations and which has associated with it visible indicating means for notifying the operator even though the latter be some distance from the device the value of the score that the 55 player is entitled to should a winning shot be made the denominations of the coin or coins with which the device had been operated and also whether or not the device had been properly or fraudulently operated. It will also be noted that the game requires a high degree of skill as the player is 60 required to properly time his shot in order to bring about a stopping of the rotatable hand 15 at one of the higher numerical designations on the dial 13.

65 In the embodiment illustrated, the playing board 19 may be removed with its associated mechanism from the casing and the necessary repairs or adjustments made thereon whenever found necessary or desirable. To facilitate the removal 70 and insertion of the playing board 19, the electric conduits leading from the batteries B are secured to fixed contacts 160 and the electric conduits connected to the mechanism arranged on the playing board are connected to the contacts 161 secured to a block 163, said contacts 161 and 160

being placed in engagement with each other when the playing board 19 is disposed within the casing 12 in fully operative position. (See Fig. 7.)

A suitable glass panel 163 may be disposed over the playing board when the device is in fully assembled position. Said glass panel prevents direct access to the ball and to the playing mechanism, and thus ensures that their use be entirely controlled by the coin operated device associated with the apparatus.

10 It is believed that my invention, its mode of construction and assembly, and many of its advantages should be readily understood from the foregoing without further description, and it should also be manifest that while a preferred 15 embodiment of the invention has been shown and described for illustrative purposes, the structural details are nevertheless capable of wide variation within the purview of my invention as defined in the appended claims.

20 What I claim and desire to secure by Letters Patent of the United States is:

1. In a game apparatus, the combination of a movably mounted member, means for moving said member and means for arresting movement 25 of said member including a projectible object a member having a playing surface onto which said object is caused to be projected, and means disposed on said playing surface in the path of travel of said projectible object for rendering said arrest- 30 ing means effective by impact of said projectible object with said last mentioned means.

2. In a game apparatus, the combination of a movably mounted member, means for moving said member and means for arresting movement of 35 said member including a projectible object, a member having a playing surface over which said projectible object is caused to travel, means for projecting the object onto the playing surface, and means provided on said playing surface in the path 40 of travel of said object for receiving the same and rendering said arresting means effective upon the receipt of the object therein.

3. In a game apparatus, the combination of a visible member movably mounted over a surface 45 provided with numerical designations, means for moving said member, and means for arresting movement of said member, said last mentioned means including a projectible object, a member having a playing surface onto which said object 50 is adapted to be projected, means for projecting said object onto the playing surface, and means disposed in the path of travel of said object for engaging the same, the engagement of said last mentioned means by said object being effective 55 for rendering said arresting means operative, whereby by proper timing of the travel of the object the said movable means may be arrested at one of the numerical designations provided on the surface over which it travels.

4. In a game apparatus, the combination of a visible rotatable member arranged for rotation over a surface provided with numerical designations, means for rotating said member and means for arresting the rotation of said member, said 65 last mentioned means including a projectible object, a member having a surface onto which said object may be projected, means for projecting said object onto said surface, means disposed in the path of travel of said object effective when 70 struck by said object for rendering said arresting means operative, and manual means for releasing said projectible object to again render said arresting means inoperative.

5. In a game apparatus, the combination of a 75

visible rotatable member arranged for rotation over a surface provided with numerical designations, a motor for driving said member, an electric circuit for said motor, and means for breaking said electric circuit to arrest said rotatable member including a projectible object, a member having a playing surface over which said projectible object is caused to travel, and switch mechanism disposed in the path of travel of said projectible object and connected in the motor circuit for breaking the motor circuit when struck by said object, whereby by proper timing of the movement of the projectible object the rotatable member may be caused to stop at one of the numerical designations provided on the surface over which it travels.

20 6. In a game apparatus, the combination of a
visible rotatable member arranged for rotation
over a surface provided with numerical designa-
tions, means for rotating said member, means
associated with said last mentioned means for
rendering the same operative for a predeter-
mined period of time and to automatically ren-
der the same inoperative at the end of said pre-
determined period of time, and means for ar-
resting the rotation of said rotatable member
before the lapse of said predetermined period of
time including a projectible object, a member
having a surface onto which said projectible ob-
ject 30 may be projected, and means disposed in
the path of travel of said object effective when
struck by said object for rendering said arrest-
ing means operative, whereby by proper timing
of the travel of said projectible object the ro-
tatable member may be arrested at one of the
35 numerical designations provided on the surface
over which it travels.

40 7. In a game apparatus, the combination of a
visible rotatable member arranged for rotation
over a surface provided with numerical designa-
tions, an electric motor for driving the same,
a circuit for said motor, means for holding said
circuit closed for a predetermined period of time,
and means for interrupting said circuit prior to
the lapse of said predetermined period of time
including a projectible object, a member having
a surface over which said object is adapted to
travel, means for projecting said object onto said
surface, and switch mechanism disposed in the
50 path of travel of said object and arranged in the
motor circuit effective for breaking the circuit
to the motor by impact of the object.

8. In a game apparatus, the combination of a visible movable member arranged for movement over a surface provided with numerical designations, means for imparting movement to said member, said last mentioned means having mechanism associated therewith for rendering the same operative for a predetermined period of time, and means for arresting the movement of said member prior to the lapse of said predetermined period of time including a projectible object, a member having a playing surface over which said projectible object is caused to travel, means for projecting said object onto said playing surface, and means arranged in the path of travel of said object for engaging the same, the engagement of said last mentioned means by said object being effective for rendering said arresting means operative, whereby by proper timing of the travel of said projectible object said movable member may be arrested at one of the numerical designations provided on the surface over which it travels.

75 9. In a game apparatus, the combination of a

rotatable member arranged for rotation over a surface provided with numerical designations, a motor for driving the same, an electric circuit for said motor, means for maintaining said circuit closed for a predetermined period of time, a plurality of fixed electrical contacts arranged for successive engagement by said rotatable member, a plurality of electric signals, an electric circuit for each of said signals, each of said circuits including one of said fixed contacts and 10 said rotatable member, and means for arresting said rotatable member including a projectible object, a member having a playing surface over which said object is adapted to travel, means for projecting said object onto said playing surface, 15 and means arranged in the path of travel of said projectible object arranged in the motor circuit effective for breaking said motor circuit by impact of said object, whereby by proper timing of the travel of said projectible object said rotatable member may be caused to stop when in 20 contacting engagement with one of the fixed contacts and to thereby close the circuit to one of the signals to actuate the same.

10. In a game apparatus, the combination of 25
a member having a playing surface, a plurality
of fixed spaced electrical contacts provided on
said surface, a rotatably mounted conducting
member for successively engaging said fixed con-
tacts, means for rotating said rotatable mem-
ber, a plurality of electric signals, an electric
circuit for each of said signals, each of said cir-
cuits including one of said fixed contacts and
said rotatable member and means for actuating
said rotatable member, said means including a 30
projectile object, means for projecting said ob-
ject onto said playing surface, and means asso-
ciated with said rotating means for said mem-
ber disposed in the path of travel of said projec-
tible object adapted for rendering said rotating 35
means ineffective when struck by said projec-
tible object, whereby by proper timing of the travel
of said projectile object said rotatable conduct-
ing member may be caused to stop when in con-
tacting engagement with one of said fixed con- 40
tacts to thereby complete a circuit to one of said
signals to actuate the same. 45

11. In a game apparatus, the combination of a
movable mounted member, means for moving said
member, a plurality of signals, means for actuating
said signals controlled by said movable mem-
ber, and means for arresting said movable mem-
ber in a signal actuating position including a
member having a playing surface, a projectible
object adapted to be projected onto said playing
surface, and means disposed in the path of travel
of said projectible object co-operating with said
movable member moving means adapted for ar-
resting said movable member when engaged by
said projectible object, whereby by proper timing
of the travel of said projectible object, said mov-
able member may be arrested at a pre-selected
position for actuating one of said signals. 55

12. In a game apparatus, the combination of a member having a playing surface, a projectible object adapted to be projected onto said playing surface, and means for projecting the same, a plurality of signals, an electric circuit for each of said signals, a plurality of fixed contacts, one of which is arranged in each of said signal circuits, a movable conducting member included in all of said signal circuits and movably mounted for successively engaging each of said fixed contacts for successively completing circuits to said signals, means for moving said movable member, 75

and means for arresting said movable member; said last mentioned means including a mechanism disposed in the path of travel of said projectile object effective for arresting movement 5 of said movable member when struck by said projectile object, whereby by proper timing of the travel of said projectile object the same may be caused to actuate the arresting mechanism at an instant when the movable member is in engagement with one of the fixed contacts and to thereby maintain one of the signal circuits in closed position to actuate one of the signals.

13. In a game apparatus, the combination of a visible rotatable member arranged for rotation 15 over a surface provided with numerical designations, a motor for rotating said member, an electric circuit for said motor, means including a clock mechanism holding said motor circuit closed for a predetermined period of time, a plurality of 20 signals, an electric circuit for each of said signals, a fixed contact arranged at each of said numerical designations and each disposed in one of said signal circuits, said rotatable member included in all of said circuits and adapted to close a 25 signal circuit every time the same is brought to a stop at one of the numerical designations, and means for arresting said rotatable member before the lapse of said predetermined period of time including a member having a track, a projectile 30 object adapted to be projected onto said track, and means disposed in the path of travel of said projectile object associated with said motor cir-

cuit adapted for breaking said motor circuit when struck by said projectile object, whereby by proper gauging of the momentum imparted to the projectile object the rotatable member may be caused to stop at one of the numerical designations to close a pre-selected signal circuit. 5

14. In a game apparatus, the combination of a visible rotatably mounted member, means for rotating said member, a plurality of signals, an electric circuit for each signal, each circuit including said rotatable member and controlled thereby, a plurality of fixed contacts, each one of which is arranged in one of said signal circuits and disposed so as to be successively engaged by said rotatable member, and means for arresting 15 said rotatable member at the correct moment to maintain one of said signal circuits in closed position including a projectile object, a member having a track onto which said projectile object may be projected, means for projecting said object onto 20 said track, and means disposed in the path of travel of said projectile object associated with said rotatable member rotating means adapted when struck by said projectile object to render said rotating means ineffective whereby by proper 25 timing of the travel of said projectile object the rotation of said rotatable member may be arrested at the instant when it is in contacting engagement with one of the fixed contacts to maintain the circuit to a pre-selected signal in closed 30 position.

KENNETH C. SHYVERS.
